C. S. ORR,
 NON-REFILLABLE BOTTLE.
 APPLICATION FILED JAN. 21, 1905.

UNITED STATES PATENT OFFICE.

CHARLES S. ORR, OF PROVIDENCE, RHODE ISLAND.

NON-REFILLABLE BOTTLE.

No. 805,810.

Specification of Letters Patent.

Patented Nov. 28, 1905.

Application filed January 21, 1905. Serial No. 242,044.

To all whom it may concern:

Be it known that I, CHARLES S. ORR, a citizen of the United States, residing at Providence, in the county of Providence and State of Rhode Island, have invented certain new and useful Improvements in Non-Refillable Bottles, of which the following is a specification, reference being had therein to the accompanying drawings.

10 My invention relates to non-refillable bottles, and has for its object the ends commonly sought in this class of devices.

To these ends my invention consists in the novel construction and combination of parts 15 hereinafter described, and set forth in the accompanying drawings, wherein—

Figure 1 is a vertical central section of the neck of a bottle embodying my invention; Fig. 2, a plan of the porcelain disk; Fig. 3, a 20 side elevation of the same; Fig. 4, a section of the inclosed parts, taken on line xx of Fig. 1; Fig. 5, a vertical central section of a portion of the bottle-neck, showing its parts in 25 reversed position and during the escape of liquid; and Fig. 6 is a like view of the same, disclosing the position of the parts after the escape of all the bottle contents and during the application of any force inwardly from the nozzle.

30 Like reference-letters indicate like parts throughout the views.

My invention is herein described in combination with a bottle-body A, having a neck B, provided with an annular rib b, in which is 35 mounted a disk C, of porcelain, glass, or similar material, traversed by a plurality of radial channels c, angular in cross-section and having a peripheral channel c', which forms a seat for a wire or ring d. Surrounding the periphery 40 of the disk C is a band or collar D, of cork, rubber, or other elastic material. The ring d assists in forcing the outer face of the collar D into the rib b of the bottle-neck and renders access of a drill or other implement more difficult. The disk is provided with legs or 45 projections c², which assist in preventing the plug from being inverted, and thus withdrawn. The band D, which is wedged intermediate its seat c' and the rib or bead b of the bottle-neck, 50 also affords a frictional resistance against removal.

Beneath the disk C is frictionally mounted in the neck of the bottle an annular plug E, of cork, rubber, rawhide, or other impervious 55 material, in whose center is frictionally mount-

ed a metallic ring or cylinder e, whose upper margin extends beyond the face of the plug E and is preferably beveled at its extremity. The lower portion of the ring e carries a plurality of arms e', which converge in a hub or bearing e², in which is fixed a vertical tube f. A metallic rod f', with an enlarged lower extremity or head f², slides in the tube f and has fixed to its upper extremity a disk or valve G, of rawhide or other suitable material. An 60 outer tube or plunger h slides upon the lower portion of the fixed tube f. The tube h has a flange h' upon its lower extremity and is provided with an annular shoulder h², against which rests the lower extremity of a spiral spring l. The upper extremity of the spring abuts against the hub e². The spring is fixed at both its extremities.

Intermediate the disk C and valve G is a float H, of cork or wood, which normally rests 70 upon the valve G.

In the mouth of the bottle-neck is a stopper I of usual form. Moving freely in the body of the bottle is a glass ball J, which is shown in Fig. 1, for convenience, adjacent the plunger h.

The operation of my invention is as follows: When the bottle is inverted, the ball J contacts with the flange h' of the plunger h, forcing the latter downwardly against the tension 80 of spring l against the hub e² of the valve-seat e, allowing the inclosed liquid to pass therethrough, as shown by the arrows in Fig. 5. The weight of the water forces the valve G away from its seat and continuing 85 traverses the channels c of the disk C, whence it escapes from the bottle. When the bottle is upright, the parts assume the position shown in Fig. 1—that is to say, the tension of the spring l retains the valve G upon its seat e, 90 by which means no liquid can pass into the bottle. The closure of the valve described is efficient even while the bottle is inverted, as shown in Fig. 6, and the attempt is made to inject liquid under pressure, since the contact 95 of the pressed liquid against the float H impels the latter against the face of the valve G, forcing the valve against its seat.

Having described my invention, what I claim is—

1. In a non-refillable bottle, the combination with a bottle-neck, of a guard beneath the stopper, a plug beneath said guard, a cylinder in said plug, a valve seated on said cylinder, a float between said guard and valve, a plun-

ger beneath said plug, a guide for said plunger held in said cylinder, and a ball adapted to contact with said plunger.

2. In a non-refillable bottle, the combination with a bottle-neck having a guard therein beneath the stopper, of a plug beneath said guard, a cylinder in said plug, a valve seated on said cylinder, a float between said guard and valve, a plunger beneath said plug, a guide for said plunger held in said cylinder, a spring around said guide and plunger and having both ends fixed, and a ball adapted to contact with said plunger.

3. In a non-refillable bottle the combination with the neck, of a guard mounted in the neck, an annular plug mounted in the neck below the disk, a valve-seat in the plug, a tube fixed in the valve-seat, a plunger slidably mounted upon the fixed tube, spring means for forcing the plunger away from the valve-seat, a valve-stem loosely mounted in the tube, a valve upon the valve-stem adapted to register with the valve-seat, and a ball adapted

to contact with the plunger when the bottle is inverted position. 25

4. In a non-refillable bottle, the combination with a bottle-neck having a guard therein beneath its stopper, of a plug beneath said guard, a cylinder in said plug with one end projecting above said plug and beveled to 30 form a seat for a valve, a valve seated on the upper beveled end of the cylinder, a float between the guard and valve, a plunger beneath the plug, a guide for the plunger held in said cylinder, a spring around said guide 35 and plunger, said spring having both ends fixed, a float between the guard and valve and contacting with the valve, and a ball adapted to contact with the plunger.

In testimony whereof I have affixed my signature in presence of two witnesses. 40

CHARLES S. ORR.
